UNITED STATES PATENT OFFICE.

FAYETTE ALLEN BILLMEYER, OF WASHINGTON, DISTRICT OF COLUMBIA.

MOTION TOY.

Application filed September 25, 1923. Serial No. 664,674.

To all whom it may concern:

Be it known that I, FAYETTE ALLEN BILLMEYER, a citizen of the United States, and resident of Washington, District of Columbia, have invented certain new and useful Improvements in Motion Toys, of which the following is a specification.

This invention relates to improvements in motion toys and consists of an amusement device of novel character adapted to be manually operated and having movable objects or figures carried upon an endless belt and supported to be operable within a fixed environment and with relation to an appropriate scene to give an impression which is realistic and attractive to the eye.

Important features of my improved device or toy structure comprise an improved arrangement of the movable parts adapted to effect the movement of the figures reversely so as to produce a succession of movable objects passing in reverse direction; an improved construction of the movable members carrying the miniature objects or figures which allows of their being more easily and economically manufactured; an improved arrangement and construction of the container permitting of its being inexpensively produced with the stationary scene printed thereon and which is so formed as to greatly facilitate the assembling of the device and accordingly reduce production cost and in addition will provide as a part of the fixed scene members so positioned in the foreground as to hide from the normal vision the operating parts and accordingly heighten the desired illusion.

In the embodiment of the features of my invention as here illustrated the scenic effect is shown as illustrating a river or harbor scene showing a portion of a city as a stationary background and wherein the movable objects are in the form of miniature ships which when moved with relation to the fixed scene will convey to the eye a realistic and satisfying effect. As will be quite apparent the scenery and figure representations may be varied to represent many other scenic effects in like manner without departing from the features of the present invention.

The several features and advantages of my present invention will be more fully understood by reference to the accompany-

ing drawings wherein like reference numerals are applied to the corresponding parts in the several views.

Figure 1 is a perspective view of my improved toy device as viewed from the front thereof.

Fig. 2 is a plan view of the parts as assembled with a portion thereof shown in cross-section better to illustrate the structure.

Fig. 3 is a view illustrating the blank employed to form the enclosing member.

Fig. 4 is a view illustrating the blank which when folded forms the foreground and supporting structure for the moving parts.

Fig. 5 illustrates the blank form of the endless belts having the figures formed integrally therewith in accordance with my invention and

Fig. 6 is a detailed view in front elevation illustrating the manner of driving the respective spools.

In the embodiment of my invention as herein illustrated the movable objects or figures 1-1 and 2-2 are mounted upon belts 3 and 4 and arranged to be moved in continuous progression lengthwise of the container and supporting member which as illustrated may desirably be in the form of a box enclosure having an open front and top and upon which is lithographed an appropriate scene or landscape. The movable figures are here shown as representations of steamships or other craft common to the harbor scene which is shown as the associated background or fixed scene. In further accordance with my invention the figures are arranged to be movable over a platform support which is suitably formed and decorated to extend the fixed scene forwardly to provide an appropriate scenic foreground which is accordingly designed to heighten the illusion as hereinafter described and in its preferred form offers an additional advantage in forming a screen to obscure from the normal vision the operating spools employed to carry the moving belts.

The enclosing and supporting parts of my improved toy are particularly designed to permit of their being made of suitable cardboard and to allow of their being economically printed and assembled so as to produce

a toy of this type which may be commercially produced at a low cost. To this end the supporting parts desirably consist of an outer enclosing member 6 5 formed from a blank, as illustrated in Fig. 3, and an inner supporting member 7 formed of a blank, as illustrated in Fig. 4. As is apparent this construction in the first 10 instance effects an economy in the printing in that it allows of obtaining the desired fixed scene by printing upon one side of the cardboard or paper only. The blank 6 as shown in Fig. 3, comprises a rectangular body or wall 8 to form the rear wall of the 15 container which has integrally formed therewith the side folds 9 and 10 which fold forwardly from its vertical side edges and a bottom fold 11 to fold forwardly from its lower longitudinal edge, as will be understood 20 by reference to Fig. 1; the parts being attached in this position by means of the tabs 12—12 integrally formed with the side folds 9 and 10 and folded inwardly over the upper surface of the bottom fold 11 and 25 attached thereto by glue or other suitable means.

The inner supporting and platform member 7 formed from the blank as illustrated in Fig. 4 comprises a vertical body portion 30 14, an upper centrally arranged platform fold 15 which is folded rearwardly to horizontal position, a marginal securing fold 16 extending longitudinally of the rearward edge of fold 15, a bottom fold 17 attached 35 to the lower longitudinal edge of body fold 14 to be turned rearwardly into horizontal position, a back fold 18 joined to the lower longitudinal edge of fold 17 and turned upwardly into vertical position to form a back 40 wall for the inner supporting member which is secured by gluing the attached fold 16 to the upper marginal edge of back fold 18. An important feature of the inner supporting member structure consists in providing 45 the front wall or body fold 14 at its end portion with the upward vertical extensions 21 and 22 formed and printed to provide appropriate foreground figures in the stationary scene so positioned as to hide the 50 supporting spools, of the operating mechanism now to be described, from the observer.

The operating parts comprise suitable spools for carrying the endless belts heretofore referred to with an exteriorly extended operating handle or lever for the manual manipulation of the device and in accordance with my improved arrangement 55 is as follows. The respective end portions 60 of the forward and rearward vertical folds 14 and 18 of the inner supporting member are provided with oppositely positioned and horizontally aligned bearing apertures 20 to receive and support at one side, the left 65 as here shown, a driving and supporting

spindle 21 and at the opposite end of the device the supporting spindle 22. The spindle 21 at its projecting forward end is bent to form an external operating lever or handle 23 and has mounted thereon the driving 70 spool 24 and an idler spool 25. The spindle 21 has an expanded key portion or projection 23 within the spool 24 whereby it is rotatably secured thereto and the spool 24 has integrally formed therewith a pulley 75 portion or pulley member 26. The opposite spindle 22 has mounted thereon idler spools 27 and 28 the latter, as shown, being formed similar to the spool 24 having integrally formed therewith a pulley or groove flange 80 29 which is reversely arranged to position the respective pulleys in longitudinal alignment. The endless belts 3 and 4, as illustrated, are carried by the spools in the arrangement whereby the upper loop is carried 85 above the horizontal platform fold 15 and the lower loops pass thereunder, the arrangement thus providing support for the upper loop and obscuring the lower or return loop from the vision. The belt 3, as 90 shown, is carried by the driving spool 24 and the idler spool 27 thus deriving its motion directly from the manipulating handle 23 to move in one direction as indicated by the arrow in Fig. 2. The other or forward belt 95 3 is carried upon the spools 25 and 28 and motion is transmitted thereto by means of a crossed belt 30 which may desirably be an elastic band engaging the respective pulley members 26 and 29 whereby the motion is 100 transmitted from the driving member 24 to the spool 28 for moving of the belt 3 in direction reverse to the movement of the rearwardly positioned belt 4.

A further important feature of my improvement consists in the improved form of belt member as herein illustrated and consists in the forming of the belts, as illustrated in Fig. 5, of paper or other suitable flexible material with the movable objects 105 or figures 1 integrally formed therewith and desirably separated partially therefrom by means of cuts 32—32. The belt with the figures thus formed integrally therewith, as will be readily understood are completed 110 by the joining of their end portions and by bending of the portions thereof forming the figures at right angles to the belt proper and into vertical position. By so forming the movable member integrally with the belt 115 very substantial economies are effected particularly with relation to the assembling operation.

As will be obvious from the construction 120 described, the turning of the operating handle 23 will transmit motion to the respective figure carrying belts to move them in opposite directions thus to produce an animated effect of a fascinating character particularly when the scenes and figures repre- 125 130

sented are reproduced from actual photographs as contemplated which adds materially to the realism of the display.

While I have illustrated and described an approved form of my invention it will be understood that various modifications thereof may be made without departing from the scope of the invention as defined in the appended claims and it is accordingly intended that all matter herein shall be interpreted as illustrative and not in a limiting sense. As illustrative thereof and as will be readily understood my device in a simplified form may be provided with but a single belt carrying the miniature figures of the character described.

Having described my invention I claim:

1. A motion toy of the character described comprising a suitable enclosing member, an inner supporting member having a horizontally positioned platform member or fold, spools suitably journaled adjacent the opposite ends of the platform folds, an endless belt carried by the spools and positioned whereby its upper loop is passed above and its lower loop is passed beneath the platform fold, means for rotating the spools and said inner supporting member adjacent its end portions being formed with forwardly positioned upwardly extended portions positioned to obscure the operating spools from normal vision and adapted to be decorated to produce a foreground scenic effect and said belt having miniature figures mounted thereon, substantially as described.

2. A motion toy of the character described having a scenic background and miniature figures adapted to be moved with relation thereto comprising a suitable supporting structure, spools suitably journaled and endless belts carried by the spools, said belts being formed of flexible material having the miniature figures formed integrally therewith, substantially as described.

3. A motion toy of the character described comprising a suitable enclosing member

decorated to provide a scenic background, an inner supporting member having a platform portion of fold, spindles suitably journaled within the inner supporting member adjacent the respective ends thereof, forwardly and rearwardly positioned spools mounted upon each of the spindles, one of said spindles being rotatably connected to its supporting spindle and said spindle having a manipulating lever thereon, forwardly and rearwardly positioned endless belts carried upon the respective spools, miniature figures mounted upon the belts, one of said rearwardly positioned spools and the forwardly positioned spool at the opposite end being provided with pulley members and a crossed driving belt carried by said pulleys whereby upon manipulation of the operating lever the figure carrying belts will move in opposite direction, substantially as described.

4. A motion toy of the character described comprising an enclosing member, an inner supporting member formed of cardboard or like material having a vertical front fold 14, a bottom fold 17 extending rearwardly and horizontally therefrom, a back fold 18 vertically positioned, a platform fold 15 bent rearwardly from the upper edge of the front fold 14 at the central portion thereof, a marginal attaching fold 16 secured to the platform fold 15, said front fold having vertical upper extensions 21 and 22 at its respective ends and said front fold and back fold being provided with bearing apertures at their respective end portions, spindles mounted in the bearing apertures, spools mounted upon the spindles, an endless belt carried by the spools miniature figures carried by the belt and a manipulating lever formed upon one of the spindles and exteriorly arranged, substantially as described.

Signed at East Orange in the county of Essex and State of New Jersey this 31st day of August A. D. 1923.

FAYETTE ALLEN BILLMEYER.
